Des. 350

Edward J. Delany of Philadelphia, Pa.
Assignee to
Geo. L. Weins, John L. Adamson & Reuben Haas of (holding under the firm of Heins & Adamson) Philadelphia, Pa.
Letters Patent No. 350. Dated February 18, 1851.

The Schedule referred to in these Letters Patent and making part of the same.

To all whom it may concern:

Be it known that I, Edward J. Delany of the City of Philadelphia, County of Philadelphia, State of Pennsylvania, have invented or produced, a new design or figure for a cast iron or brass umbrella stand, and I do hereby declare that the following is a full and exact description of the same.

What your petitioner claims as new & desires to secure by Letters Patent, is the peculiar ornamental design or figure as shown in the accompanying drawing.
